CANTILEVER SPRING

James W. Pettit, Portland, Oreg.

Application October 24, 1942, Serial No. 463,203

1 Claim. (Cl. 5—236)

This invention relates generally to springs for beds and upholstered furniture, and particularly to a cantilever spring.

The main object of this invention is to construct a spring adapted to the use of non-metallic materials such as wood.

The second object is to provide a spring of the class described which will insure the maximum amount of comfort and adjustability for spring tension.

The third object is to construct a spring which will be light in weight, not inclined to sag, and not requiring metals essential in other activities.

These and other objects are accomplished in the manner set forth in the following specification, as illustrated in the accompanying drawing, in which:

Fig. 1 is a plan of the spring.

Fig. 2 is a side elevation of the spring.

Fig. 3 is a section taken along the line 3—3 in Fig. 2.

Fig. 4 is a section taken along the line 4—4 in Fig. 2.

Fig. 5 is a section taken along the line 5—5 in Fig. 2.

Similar numerals refer to similar parts throughout the several views.

Referring in detail to the drawing, there is shown a rectangular frame consisting of the sides 10 and ends 11 suitably secured at the corners 12. Along the top edge of each end 11 is secured a strip 13.

Along each side 10 is secured an inclined strip 14 which affords rigidity to the sides 10 and forms a support for the transverse fulcrum bars 15 which are notched at the ends 16 to receive the inclined strips 14. The bars 15 are also provided with notches 17 on their upper sides to receive the upper spring leaves 18 and the lower spring leaves 19, the purpose of which is to afford the greatest amount of strength at the point of greatest stress—namely, over the fulcrum bar 15.

It is also desirable to round the end 21 as illustrated, to prevent same from engaging the contacting materials.

It is desirable to provide a loose double lacing of heavy cord 22 in basket weave fashion around the spring ends 21 as shown, in order to unify the spring elements and resist the tendency to

sag. It is also desirable to provide a transverse tie 23 across the middle of the unit directly under the spring ends 21, and to unite each spring end 21 to the tie 23 by means of a cord 24 in order to provide a desired amount of initial tension to the leaves.

Obviously, the sizes and proportions of the parts will depend upon the purpose for which they are used, as well as the materials from which they are made.

It can be seen from the foregoing, that by means of this construction, there is provided an inexpensive, comfortable, and practical spring unit which lends itself to use in connection with furniture, automobile cushions, etc. greatly lightening the unit and avoiding the use of essential war materials. For small units, single cantilevers would be employed instead of the double as shown.

20 The purpose in inclining the members 14 is to provide adjustability for the spring tension in the members 18 and 19. That is, as the bars 15 are moved toward the middle of the structure, the strength of the spring is increased, and as 25 the bars 15 are moved toward the ends 11, the springs are rendered more flexible. Owing to the flatness of the angle of the members 14 it is not necessary to provide any means for preventing the movement thereof.

30 I claim:

In the cantilever spring unit, the combination of a rectangular frame having fulcrum bars placed transversely across same near the ends thereof, each of said fulcrum bars having resting thereon a plurality of inclined spring leaves, one end of each of which is supported by the end of the frame and the other end of which is unsupported and extends beyond the center of the spring frame, the spring leaves from the two sets 40 of fulcrum bars alternating, inclined cleats on said frame substantially parallel with said leaves and supporting said bars, said bars being adjustable along said leaves, and flexible means for uniting the overlapping ends of said leaves, and tie 45 strings between said overlapping leaf ends and said frame adapted to impose an initial tension on said leaves.

JAMES W. PETTIT.
